225,700

SEAM RIPPER

Herman Ament, 60 Marbledale Road,
Tuckahoe, N.Y. 10707

Filed Oct. 26, 1970, Ser. No. 25,652

Term of patent 14 years

Int. Cl. D6—99

U.S. Cl. D3—19

FIG. 1 is a side elevational view of a seam ripper showing my new design;

FIG. 2 is a front perspective view thereof with the cap removed;

FIG. 3 is a rear perspective view thereof;

FIG. 4 is a cross sectional view on the line 4—4 of FIG. 1;

FIG. 5 is a cross sectional view on the line 5—5 of FIG. 1; and

FIG. 6 is a cross sectional view on the line 6—6 of FIG. 1.

I claim:

The ornamental design for a seam ripper, substantially as shown.
